UNITED STATES PATENT OFFICE.

FRANK W. BARROWS, OF BRIDGEPORT, CONNECTICUT, ASSIGNOR TO COLUMBIA GRAPHOPHONE MANUFACTURING COMPANY, OF BRIDGEPORT, CONNECTICUT, A CORPORATION OF DELAWARE.

SAFETY EJECTOR FOR DICTAPHONES AND THE LIKE.

Application filed March 25, 1922. Serial No. 546,739.

To all whom it may concern:

Be it known that I, FRANK W. BARROWS, a citizen of the United States, and a resident of the city of Bridgeport, county of Fairfield and State of Connecticut, have invented certain new and useful Improvements in a Safety Ejector for Dictaphones and the like, of which the following, taken in connection with the accompanying drawings, is a specification.

This invention relates to a safety ejector or sound-record throw-off for dictating machines and the like, particularly for use in connection with cylinder phonographs of the "dictaphone" type. The invention is an improvement over the throw-off devices, heretofore in use, and particularly over such devices as disclosed, for example, in the United States patents to Haines, #1,005,025 of October 3, 1911, and Macdonald, #1,152,529 of September 7, 1915. These patents disclose throw-off devices, which are at all times in operative position, and adapted to force a cylindrical record from engagement with its mandrel, so that it can be removed without engaging the fingers with the record surface.

Inasmuch as dictators often use the entire cylinder right up to the very end, and, consequently, allow the carriage to feed beyond the bell signal to the end of the feed screw, the recording stylus will, in such cases, drop off the end of the cylinder to the limit of its stop, which is below the surface of the cylinder. With the devices heretofore in use, the dictator might then inadvertently eject the cylinder from the mandrel with the throw-off mechanism, without first lifting the sound-box, consequently thrusting the end of the cylinder forcibly against the styli and damaging them. Also, dictators might—and often did—stop the carriage at the bell signal, but, subsequently, inadvertently eject the cylinder before lifting the recording or reproducing stylus from the cylinder, consequently cutting a deep line across the length of the cylinder.

An object of this invention is to provide a throw-off device, which will be operative only when the sound-box of the machine is raised from the sound-record, so that the possibility of ejecting the record, while the stylus is engaged therewith, and the result-

ing damage to the record and stylus, is entirely eliminated.

Another object is to devise a new and useful mechanical movement, such that the movement of one member will be permitted when a corollary member is in a predetermined position, but prevented when said last-named member is in another predetermined position, said mechanical movement being effected through a single connection between the members.

Other objects are to provide a device of this character, which will be of simple construction, and which will be entirely efficient in operation.

With these and other objects in view, an embodiment of the invention is shown in the accompanying drawings, and this embodiment will be hereinafter more fully described with reference thereto, and, finally, the invention pointed out in claims.

In the accompanying drawings—
Fig. 1 is a combined vertical sectional view and incomplete side elevation of a dictating machine in which an embodiment of the present invention is incorporated, this view being taken along the line 1—1 of Fig. 2;

Fig. 2 is a plan view of the machine, partially broken away to disclose the working parts;

Fig. 3 is a similar view, only taken from the rear;

Fig. 4 is a combined vertical sectional view and side elevation, taken along the line 4—4 of Fig. 3; and

Fig. 5 is a perspective view of the operative elements of the present embodiment of the invention, the associated structure being removed.

Similar reference characters indicate corresponding parts throughout the several figures of the drawings.

Referring to the drawings, the embodiment of the invention disclosed therein is shown as incorporated in a sound recording and reproducing machine of the "dictaphone" type.

The bed-plate 10 is provided at its ends, adjacent the rear edge, with standards 11 and 12, and at one end forwardly of the standard 11, with an inwardly-extending hollow bearing portion 13, in which is jour-

naled the shaft 14. This shaft mounts the record-supporting tapered mandrel 15 at one end, and is provided at its other end with a belt pulley 16, over which extends a 5 driving belt 17 adapted to be driven from a suitable motor (not shown).

The sound-box carriage 18 is mounted for longitudinal movement along a hollow slotted shaft 19, rigidly supported at its 10 ends in the standards 11 and 12 and in which is provided a feed screw adapted to advance the carriage longitudinally of the mandrel, as is usual in such machines. The carriage is maintained against rotation about the 15 shaft 19 by means of a support 20 bifurcated at its lower end, and slidably engaging a bar 21 supported at its ends in the standards 11 and 12. A sound-box or "speaker" 22 is mounted in the sound-box carriage, 20 and is provided with both recording and reproducing styli 23 and 24, and is adapted to be moved into any one of three positions—recording, neutral, or reproducing—by means of a lever 25 projecting upward- 25 ly from the carriage, and having a hub-portion 26 journaled upon the shaft 19. The peripheral portion of the hub is exposed through a slot 27 provided in the rear portion of the carriage casing.

30 In Fig. 1, the neutral position is indicated in full lines, the sound-box being raised from engagement with the sound-record. The long dash lines indicate the recording position; and the short dash lines 35 the reproducing position—the sound-box being lowered in these two latter positions. This type of sound-box carriage and shifting mechanism, which is merely illustrated as exemplary, is disclosed in United States 40 patent to Macdonald, #1,100,024, dated June 16, 1914, to which reference may be had for a further detailed description thereof.

Within the hollow bearing portion 13, 45 there is provided a boss 28 having a cylindrical bore, in which is slidably mounted a shaft 29 provided at its end with an arcuate head 30, disposed in concentric and upwardly spaced relation to the surface 50 of the mandrel. Normally, the head 30 is seated in a recess 31 provided in the front wall of the portion 13, and upon outward reciprocation of the shaft 29 is adapted to engage the end of the cylindrical record 55 mounted on the mandrel 15 and force it outwardly, thereby permitting it to be removed by inserting the fingers within its bore. The inner end of the shaft 29 is provided with a recess 32 having opposed V- 60 shaped end walls and in which is engaged the end of a crank arm 33 mounted upon the lower end of a vertical rock-shaft 34, journaled in a bearing boss 35 provided upon the portion 13, and provided at its upper 65 end with a laterally-extending handle 36.

A spring 37 is coiled about the shaft, and has one end hooked about the crank arm 33 and its other end restrained by engagement with the inner wall of the portion 13, the spring normally maintaining the shaft 29 70 in its retracted position. The shaft is adapted to be reciprocated outwardly to remove a record by turning the handle 36.

The shaft 29 is provided upon its under-side with a straight-sided cut-out or notch 75 38 normally registering with a slot 60 in the boss 28, and in which the end of a lever-arm 39, extending through a slot 40 in the portion 13, is adapted to be engaged and disengaged to respectively lock and release 80 the shaft 29. The lever-arm 39 is provided with a hub-portion 41, fixed by means of a set screw 42 upon a shaft 43 of non-circular cross section—square, as shown—and having its cylindrical ends 44 (Fig. 2) journaled for rotation in bearing bushings 45, adjustably mounted in the standards 11 and 12, and fixed against longitudinal movement by set screws 46.

Upon the square shaft 43, there is provided a lever 47 slidably mounted for rotary movement therewith, its hub 48 having a bore corresponding to the cross section of the shaft, and being provided with reduced bearing ends 49 and 50 (Fig. 2), 90 journaled in the parallel side portions 51 and 52 of a bracket 53, secured at the rear side of the sound-box carriage by screws 54.

The upper end of the lever is provided with a tooth 55, which is held in engagement with a projecting cam-portion 56 of the hub-portion of the lever 25, by means of a spring 57 (Figs. 1 and 4) tied between the lever 47 and a lug 58 formed on the bracket 53. 105

The cam-portion 56 is provided with a depression or notch 59, into which the tooth 55 is adapted to engage, and at each side of the depression, there are provided raised portions formed concentric to the axis of 110 rotation of the lever 25. The notch 59 is engaged by the tooth 55 in the neutral position of the lever 25—and in which position, the sound-box is raised from the surface of the record—the lever arm 39 being 115 moved in this position, through the rotation of the shaft 43, out of engagement with the notch 38 of the shaft 29, and thereby permitting the throw-off mechanism to be operated to remove the record from the mandrel. In the other positions of the lever 25, and in which the sound-box is engaged with the record surface, the tooth 55 is forced out of the notch 59, and engages one or the other of the concentric raised surfaces of the cam-portion 56, thereby moving the end of the lever 39 into locking engagement with the notch 38 of the shaft 29, 125 and preventing operation of the ejecting mechanism. 130

Thus, it is seen that it is only possible to remove the record from the mandrel by means of the ejecting mechanism when the lever 25 is in neutral position, and the sound-box is raised from engagement with the record surface. The chance of damaging the record surface or the styli, by removal of the record while the sound-box is in either recording or reproducing position, 10 is entirely removed.

The device is of extremely simple construction and operation, and can be conveniently incorporated in new machines, or supplied as an attachment for machines that are 15 in use.

While the invention is illustrated in the drawings and described with particularity, as applied to a talking-machine of a certain type, it is to be especially understood that 20 it is not restricted to the form shown, or to any of the specific details thereof, as, obviously, changes in construction and design can be made without departing from the invention, and without affecting the different 25 sub-combinations thereof. Moreover, certain features of the invention are capable of use without other features thereof. Such changes are, of course, contemplated by the invention and would not constitute any departure therefrom, as defined in the appended claims.

Having described the invention, what is claimed is:

1. In a machine of the character described, a record-support, means for removing a record therefrom, a sound-box adapted to be engaged with and disengaged from the record, and means adapted to prevent operation of said first-named means and 40 rendered operative through engagement of the sound-box with the record.

2. In a machine of the character described, a record-support, means for removing a record therefrom, a sound-box adapted 45 to be engaged with and disengaged from the record, and means adapted to prevent removal of the record by said first-named means and rendered operative through engagement of the sound-box with the record.

50 3. In a machine of the character described, a support for cylindrical records, a sound-box adapted to be raised and lowered, record-ejecting means, and means adapted to prevent operation of the record-ejecting 55 means and rendered operative through the lowering of the sound-box.

60 4. In a machine of the character described, a support for cylindrical records, a sound-box, means for moving the sound-box into recording, or reproducing, or neutral positions, record-ejecting means, and cooperative locking means between the record-ejecting means and the sound-box moving means adapted to lock the ejecting 65 means in the recording or reproducing po-

sition of the sound-box and to release it in the neutral position.

5. In a machine of the character described, means whereby the record is ejected from the record-support, and means whereby said first means is made inoperative through the engagement of the sound-box with the record. 70

6. In a machine of the character described, means whereby the record is ejected 75 from the record-support, and means whereby said first means is made inoperative through movement of the sound-box to position to engage the record.

7. In a machine of the character described, the combination with a record-support and a sound-box, of means for ejecting a record from said support, and means for rendering said first means inoperative through movement to record-engaging position of the sound-box. 80

8. In a machine of the character described, the combination with a phonograph record and a sound-box, of a support for the record, means for ejecting the record 90 from its support, and means for rendering said first means inoperative through movement to record-engaging position of the sound-box.

9. In a machine of the character described, the combination with a cylindrical phonograph record and a sound-box, of a mandrel for the record, means for ejecting the record from its mandrel, and means for rendering said first means inoperative 95 through movement to record-engaging position of the sound-box.

10. In a machine of the character described, the combination with a cylindrical phonograph record and a sound-box, of a mandrel for the record, means for ejecting the record from its mandrel by engagement with the end thereof, means adapted to lock said ejector-means in retracted position, means for shifting the sound-box into and 100 out of record-engaging position, and means controlled by the shifting means adapted to operate said locking means to release the ejector means in the disengaged position of the sound-box.

11. In a machine of the character described, the combination with a cylindrical phonograph record and a sound-box, of a mandrel for the record, means for ejecting the record from its mandrel by engagement with the end thereof, means adapted to lock said ejector means in retracted position, means for shifting the sound-box into and out of record-engaging position, and cam means controlled by the shifting means 110 adapted to operate said locking means to release the ejector means in the disengaged position of the sound-box. 120

12. In a record-ejector mechanism, means for locking and releasing the ejector, and 130

means for operatively connecting it to the sound-box raising and lowering mechanism of a phonograph, whereby said first means is adapted to lock the ejector mechanism in the lowered position of the sound-box and to release it in the raised position.

13. In a machine of the character described, a record-support, a longitudinally movable sound-box, ejector means for removing a record from the support, locking means therefor and means connected to said locking means and moving with the sound-box, and adapted to operate the locking means to release the ejector when the sound-box is disengaged from a record.

14. In a machine of the character described, a record-support, a movable sound-box carriage, a sound-box, sound-box-shifting means adapted to move the sound-box into and out of record-engaging position, means whereby the record is ejected from the record-support, a locking lever adapted to engage said means to lock it, a rock-shaft supporting said lever, a record-lever rotatable with the rock-shaft and movable with the sound-box carriage, and means controlled by said sound-box-shifting means adapted to operate said record-lever to ro-

tate the rock-shaft and said locking lever, whereby said ejecting means is respectively locked and released in the engaged and disengaged positions of the sound-box with the record. 30

15. In combination, a movement imparting member, a second member adapted to cooperate with an article to be moved by said first member, and means cooperatively relating said members to permit movement of the first member when the second member is in one predetermined position, and to 35 prevent such movement when it is in another predetermined position.

16. In combination, a movement imparting member, a second member adapted to cooperate with an article to be moved by 40 said first member, and means to permit movement of the first member when the second member is in one predetermined position, and to prevent such movement when it is in another predetermined position, said 45 means including a single connection operatively relating the members.

Signed at Bridgeport, in the county of Fairfield, and State of Connecticut, this 23rd day of March, A. D. 1922.

FRANK W. BARROWS.
